UNITED STATES PATENT OFFICE.

CHARLES G. KAISER, OF PORTLAND, OREGON.

FURNACE.

Application filed March 5, 1925. Serial No. 12,153.

My invention relates to furnaces in general, and particularly to gas furnaces, the object being to provide a furnace that will utilize the heat units to better advantage than heretofore, and that shall be of simple and economical construction.

I accomplish these objects by means of the construction illustrated in the accompanying drawings, which are a part of this 10 application for Letters Patent, like characters of reference indicating like parts throughout the several views thereof, and in which:

Fig. 1 is a perspective view of my furnace, 15 with parts broken away to illustrate the construction.

Fig. 2 is a sectional elevation upon line 2—2 of Fig. 1.

Fig. 3 is a sectional elevation upon line 20 3—3 of Fig. 1.

Fig. 4 is a sectional plan upon line 4—4 of Fig. 2.

Fig. 5 is a fragmentary perspective view 25 of the front end of the combustion chamber and exhaust flue.

In general my device consists of a combustion chamber having two horizontal parts connected with a vertical part; a chambered member surrounding said combustion chamber and connected to the upper horizontal 30 part thereof, with a space intermediate said combustion chamber and said chambered member, and having tubes passing through said latter chamber; an exhaust flue connected with the bottom of said chambered member opposite the side thereof connected with said combustion chamber; and a casing surrounding said chambered member, and spaced therefrom.

40 The combustion chamber is composed of a lower horizontal part 6, in which is located the gas burner, not shown in the drawings, which gas burner is supplied by a pipe 7; an upper horizontal part 8, which is connected with a chambered member herein-after to be described; and a vertical part 9 connecting the rear ends of said horizontal parts 6 and 8, as shown in Figs. 1 and 3.

45 The chambered member surrounding the combustion chamber is a box-like member composed of an inner wall 10 surrounding the combustion chamber and spaced therefrom as shown in Fig. 4; an outer wall 11 surrounding said inner wall and spaced 50 therefrom, as shown also in Fig. 4; and a top

wall 12 and bottom wall 13 closing each end of the space between said walls 10 and 11. The space inclosed by said inner wall 10 is occupied by the combustion chamber, the lower horizontal part thereof passing below 60 said chambered member, the vertical part 9 thereof passing upward adjacent the rear of said chambered member, and the upper horizontal part 8 thereof being connected with said chambered member at the upper 65 portion of the front as shown in Figs. 1 and 3.

Each side portion of the chambered member is provided with inclined tubes 15 as shown in Fig. 2 passing therethrough, and each end portion of said chambered member is provided with vertical tubes 16 passing therethrough as shown in Figs. 1 and 3.

The rear portion of said chambered member is connected at its bottom by a pipe 17 75 to a horizontal flue 18, which flue passes beneath the lower horizontal part of the combustion chamber, and at its front end connects with a chimney flue 19. A water receptacle 20 surrounds the flue 18 for the purpose of keeping water therein to cool said flue, thus condensing any water vapor that may be in the products of combustion, and utilizing to the utmost all heat units in the 80 gas fuel.

An outer casing 21 surrounds the entire structure above described, and is spaced therefrom, as shown in Figs. 2, 3 and 4, and the heat is distributed from the dome thereof by suitable pipes 22.

90 The products of combustion pass upward in the combustion chamber through part 9 thereof, and enter the chambered member through part 8 of the combustion chamber. Thence they pass around through said chambered member heating the walls thereof and the tubes therein, and pass out therefrom by pipe 17 into the flue 18, and finally out of the furnace by the chimney flue 19.

95 The air to be heated passes into the furnace at the bottom of the casing 21 and there divides, taking one of several passages through the furnace; part of the air passes directly up and is heated by the outer wall of the chambered member 11. Part passes 100 beneath said chambered member and upward through the space between said chambered member and the combustion chamber. Part passes beneath the chambered member and upward through the vertical tubes 16 there- 105 110

in. And part passes from the space between the chambered member and the casing into the space between said chambered member and the combustion chamber by way of 5 the inclined tubes 15, the streams of air thus directed impinging upon the heated combustion chamber and thus being heated to a very high temperature.

10 The heated air passing through the several passageways just described is gathered at the top of the furnace by a hood 26 and thus directed into the furnace dome.

15 By this construction the heat units are nearly all extracted from the fuel and used 20 to heat the air, and the products of combustion entering the chimney flue 19 are nearly cold.

25 My device may be constructed of any materials deemed convenient and suitable for a 30 device of this character, and while I have illustrated and described a form of construction and arrangement of parts found desirable in materializing my invention, I wish to include in this application all mechanical equivalents and substitutes that 35 may be fairly considered to come within the scope and purview of my invention as defined in the appended claims.

Having disclosed my invention so that 40 others may be enabled to construct and to use the same, what I claim as new and desire to secure by Letters Patent is:

1. In a furnace; a combustion chamber; 45 a chambered member surrounding said combustion chamber and spaced therefrom; a casing surrounding said chambered member and spaced therefrom; and inclined tubes 50 passing through said chambered member from the space between said chambered member and said casing to the space between said chambered member and said

combustion chamber, and directed towards the latter.

2. In a furnace; a combustion chamber having two horizontal portions connected 45 by a vertical portion; a flue beneath said lower vertical portion; a water receptacle surrounding said flue; and a chambered member forming passageways for the products of combustion connecting said upper 50 horizontal portion of the combustion chamber with said flue.

3. In a furnace; a combustion chamber composed of an upper and lower horizontally positioned portions and a rearwardly disposed vertical portion connecting said horizontal portions; a chambered member surrounding said combustion chamber with a space intermediate the adjacent walls of said chamber and said member, the upper portion 60 of said combustion chamber leading into said chambered member; a flue beneath said combustion chamber; a pipe connecting said flue and said chambered member; and inclined tubes passing through said chambered member into said space. 65

4. In a furnace; a combustion chamber composed of a lower horizontal part, an upper horizontal part, and a vertical part connecting the rear ends of said horizontal parts; and a chambered member surrounding said combustion chamber with a space between the adjacent walls of said chamber and said member; said member being connected to the forward end of said upper part 70 of the combustion chamber. 75

In witness whereof I claim the foregoing as my own I hereunto affix my signature at Portland, county of Multnomah, State of Oregon, this 27th day of Feb., 1925.

CHARLES G. KAISER.
